United States Patent Office.

JAMES ROBINSON, OF FUNKVILLE, PENNSYLVANIA, ASSIGNOR TO HIMSELF
AND WILLIAM ROBINSON, OF BROOKLYN, NEW YORK.

Letters Patent No. 77,100, dated April 21, 1868; antedated April 9, 1868.

IMPROVEMENTS IN LAMP-CHIMNEYS.

The Schedule referred to in these Letters Patent and making part of the same.

TO ALL WHOM IT MAY CONCERN:

Be it known that I, JAMES ROBINSON, of Funkville, in the county of Venango, and State of Pennsylvania, have invented certain new and useful Improvements in Lamp-Chimneys; and I do hereby declare that the following is a full, clear, and exact description of the same, reference being had to the accompanying drawings, making a portion of this specification, in which—

Figure 1 is a side view of a lamp-chimney constructed according to my invention.

Figure 2 is an inverted plan view of the same.

Figure 3 is a horizontal transverse section of the same, showing it as applied to a burner.

Similar letters of reference indicate corresponding parts in all the figures.

This invention consists in a lamp-chimney, having a notch formed in one side of the annular flanch, at the base thereof, with the material partially severed from said flanch, raised up to form a lip at one side of said notch, so as to act as a stop against the chimney being turned too far, and as a guide to enable the chimney to be readily removed from the burner when required.

To enable others to understand the nature and construction of my invention, I will proceed to describe it with reference to the drawings.

The chimney, made preferably of glass, and of any suitable size and form, is marked A in the drawings, and the annular flanch, which projects outward from the base thereof, is represented at a. The said flanch has formed, in one side or edge thereof, a notch or recess, a', situated at one side of which, and formed upon the flanch a, is an upwardly-projecting spur or lip, b'.

The top of the burner should be furnished with inwardly-projecting studs or ears, marked, respectively, a* b* c*, for convenience of description; and placed at different parts of the periphery of the said top, as shown in fig. 3, and with a space between the said ears and the top-plate of the burner, corresponding to or slightly exceeding the thickness of the flanch a of the chimney.

In attaching the chimney to the burner, one side of the flanch a is first pressed or placed under the studs or ears b* c*, with the notch or recess a' immediately over the remaining ear, a*, and such notched side of the flanch being pressed downward, so that the ear a* is caused to pass up through and be brought above the said notch, whereupon the chimney is turned around upon its vertical axis, so that the notch a' is brought away from underneath the ear a* into the position shown in fig. 3, and the flanch c, being brought under and confined below the several ears a* b* c*, the chimney is effectually secured to the burner.

When it is desired to detach the chimney, it is turned back until the lip b' strikes the side of the ear a*, and stops the turning of the chimney, when the notch a' thereof is brought underneath the ear a*, which, being done, the chimney is tilted so as to bring the notched side of the flanch a above the ear just mentioned, and the opposite side of such flanch is then slipped from under the other ears, b* c*, the lip thus serving as a guide to facilitate the bringing of the notch a' under the spur a* in such removal of the chimney.

This invention may not only be employed in the construction of chimneys proper, but the so-called "globes" for lamps and gas-burners may also be made on the same principle for a corresponding purpose.

What I claim as my invention, and desire to secure by Letters Patent, is—

The lip b, formed of the partially-severed material of the flanch c, in the formation of the notch or recess a', substantially as and for the purposes set forth.

JAS. ROBINSON.
